UNITED STATES PATENT OFFICE.

CHARLES G. SINGELYN, OF DETROIT, MICHIGAN.

AUTOMATIC AIR REGULATOR FOR AUTOMOBILE GAS-ENGINES.

1,357,355.

Specification of Letters Patent.

Patented Nov. 2, 1920.

Application filed July 28, 1919. Serial No. 313,870.

To all whom it may concern:

Be it known that I, CHARLES G. SINGELYN, a citizen of the United States, residing at Detroit, county of Wayne, State of Michigan, have invented a certain new and useful Improvement in Automatic Air-Regulators for Automobile Gas-Engines, and declare the following to be a full, clear, and exact description of the same, such as will enable others skilled in the art to which it pertains to make and use the same, reference being had to the accompanying drawings, which form a part of this specification:

My invention relates to an improvement for gas engines for motor vehicles.

The object is to provide means whereby an additional supply of air will be admitted to the gas mixture as the running speed of the engine increases.

An additional object is to provide such means whereby the quantity of air thus admitted will vary directly as the running speed increases and such additional supply will be automatically shut off as the amount of fuel passing through the intake falls below a certain minimum.

An additional object is to provide inexpensive simple means connected up with the throttle rod so that actuation thereof to increase the fuel supply will automatically furnish an additional air supply to the engine, the reverse likewise being true.

In the drawings:

Figure 1 is a conventional gas engine with my improvement attached.

Fig. 2 is a detail sectional view.

A form of conventional gas engine is represented by *a*, the gas intake pipe is represented by *b*, accelerator rod *c* is connected up by means of link *d* to bell crank *e* at the lower extremity of the throttle rod. *f* indicates a plunger guide, having an interior air passageway *p* which communicates with the atmosphere through air inlet holes *i*. Plunger guide *f* is screwed or otherwise inserted through the wall of the gas intake pipe, the interior air passageway *p* communicating with the gas intake pipe. Within the plunger guide is disposed a plunger *g* held there-in by means of a spring *h*, so as to normally cover air inlet holes *i*. A flexible linkage is provided connecting said plunger with the accelerator rod. A telescopic link is here shown consisting of a rod *k* held telescopically within tubular member *j*. A stop *g*² is provided on the plunger, a stop *j*² is pro-

vided on the telescopic link. When the accelerator rod has been withdrawn sufficiently to bring link *j* as it pivots about its pivotal point on plunger *g* into a perpendicular position thereto stop *j*² is brought into contact with stop *g*² and further rotation of the link about its pivotal point on the plunger is prevented. Plunger *g* is then withdrawn equally with the accelerator rod.

For example, let the position *m* indicate the throttle valve as closed. The plunger is held seated in the plunger guide and the air inlet holes are closed thereby. *n* would indicate the position of the link *j* up to the time the accelerator rod had been actuated such distance that it would begin to actuate the plunger and would be adjusted in such a manner as to provide sufficient inlet of gas to the engine to attain a predetermined engine speed. Passing point *n* or after this predetermined engine speed has been passed, the plunger will be actuated equally with the accelerator rod uncovering air inlet holes in proportion to its actuation, thereby admitting air to the intake in proportion to the increase of gas flow therein. It will be apparent that the withdrawal of the plunger and consequent uncovering of air inlet holes in the plunger will bear a direct ratio to the admission of fuel to the engine as regulated by the operation of the throttle rod.

It will be observed that rod *c* would be actuated by the accelerator pedal the same as through link *d* connecting the same up to the throttle rod. The primary purpose however is to provide means whereby as the flow of fuel to the engine is increased after the passing of said minimum rate of flow has been reached, additional air supply would be automatically admitted to the gas mixture proportionate therewith and this would normally be accomplished through the throttle rod.

What I claim is:

1. In a gas engine for motor vehicles, in combination with the gas inlet pipe a plunger guide having an air passageway leading therein such air passageway communicating with the atmosphere by means of a series of air inlet holes, a plunger disposed in said plunger guide normally closing said air inlet holes, means connecting said plunger with the throttle rod, such means so adapted that after the throttle rod has been actuated a predetermined distance the plunger will commence to withdraw, uncovering the

air inlet holes in the plunger guide in direct proportion to the further actuation of said throttle rod beyond such predetermined distance.

5. 2. In a gas engine for motor vehicles, the combination with an intake pipe, of a plunger guide fitted thereto, such plunger guide being provided with an interior air passageway leading to the intake pipe and communicating with the atmosphere by means of air inlet openings, a plunger disposed in said plunger guide, a tension spring normally holding said plunger seated in the plunger guide closing the air inlet openings, a telescopic link connecting pivotally with said plunger and the accelerator rod, a stop on said plunger, a stop on said link adapted to coact with the stop on the plunger when the link has been actuated a predetermined distance by the movement of the accelerator rod and to withdraw the plunger equally with the accelerator rod after the same arrives in such perpendicular position, means connecting the accelerator rod with the 20 throttle rod so the same may be actuated thereby.
3. In a gas engine for motor vehicles, in combination with a gas inlet pipe, a plunger guide fitted thereto, provided with an interior air passageway leading to the interior of the inlet pipe and communicating with the atmosphere by means of air inlet openings, a plunger disposed in said plunger guide, normally closing said inlet opening, means connecting said plunger with the throttle rod in such a manner that the throttle rod may be actuated a predetermined distance before said means will actuate said plunger, means provided so that after said 30 throttle rod has been actuated said predetermined distance the plunger will be with-

drawn directly in proportion to the actuation of the throttle rod uncovering the air inlet openings.

4. In a gas engine for motor vehicles, in combination with a gas inlet pipe, a plunger guide fitted thereto and provided with an interior air passageway leading to the interior of the inlet pipe communicating with the atmosphere by means of air inlet openings, a plunger disposed in said plunger guide normally closing said air inlet openings, a telescoping link connecting said plunger with the throttle rod, means provided whereby after said telescoping link has been actuated a predetermined distance said link will withdraw said plunger uncovering said air inlet openings in direct proportion to the further actuation of said link.

5. In a gas engine for motor vehicles, in combination with the gas inlet pipe, a plunger guide fitted thereto, said plunger guide provided with an interior air passageway leading into the inlet pipe and communicating with the atmosphere by means of air inlet openings in the plunger guide, a plunger disposed in said guide normally closing said air inlet opening, a telescoping link connecting said plunger with the throttle rod, a stop carried on said plunger, a stop carried on said telescoping link adapted to be brought into engagement with the stop on the plunger after the link has been actuated a predetermined distance by the throttle rod and to coact with the stop on the plunger so that the plunger will be withdrawn uncovering said air inlet openings in direct proportion to the actuation of the link by the throttle rod.

In testimony whereof, I sign this specification.

CHARLES G. SINGELYN.
